UNITED STATES PATENT OFFICE.

FREDERIC H. FIELD, OF PROVIDENCE, RHODE ISLAND.

FIRE-ALARM INDICATOR AND RECORDER.

SPECIFICATION forming part of Letters Patent No. 288,221, dated November 13, 1883.

Application filed August 13, 1883. (No model.)

To all whom it may concern:

Be it known that I, FREDERIC H. FIELD, a citizen of the United States, residing at Providence, in the county of Providence and State of Rhode Island, have invented a new and useful Fire-Alarm Indicator and Recorder, of which the following is a specification.

My invention relates to improvements in a fire-alarm indicator and recorder, which is an appendage to the fire-alarm apparatus used in fire hose or engine stations, and which correctly designates the locality of a fire by indicating, through the medium of numerals, the number of strokes upon a bell at different intervals, and also to record upon a ribbon of paper the number of the strokes of the bell; and the object of my improvement is the combination of the indicator and recorder by means of mechanical arrangements hereinafter described, and which are illustrated in the accompanying drawings, in which—

Figure 1 is a front elevation of the indicator and recorder, and Figs. 2 and 3 are sectional views of mechanism operating the indicator. Fig. 4 is a perspective view of cams f' , i , and i' .

Similar letters refer to similar parts throughout the several views.

The back A, intermediate plate, B, and guide-piece C, support the mechanism of the apparatus. At each movement of the hammer, which is operated by the fire-alarm mechanism now in use to strike the alarm-bell, the lever D is raised, which, being connected by means of the arm E and rod F to the lever G, causes said lever also to rise.

The lever G has attached to it the arms a a' a'' , which respectively support the two levers b b' and point b'' . The lever b has its upper end hooked, for the purpose of catching onto one of the three pins c which project from the side of gear 1, and prevents said gear from turning when the alarm is not in action. When the alarm is in action and is to strike but once, lever b is released from pin c and drops back into the space f''' , and as gear 1 revolves the cam f' springs the hook to one side until it is brought in contact with the next pin c , upon which it catches and stops the gear; but should the alarm be struck more than once the hook drops on the outside of cam f' and passes over second pin, c , but catches upon the third pin, c .

Gear 1 has attached to it the drum c' , around which passes the ribbon of paper d , which is drawn from the roll d' , while the alarm is in action, by means of the weight e , which revolves said drum. The friction-roll e' prevents said paper from slipping on the drum. The recording-point b'' is attached to and receives its motion to perforate the paper d from lever G.

The end of arm a' , at each stroke of the alarm, is made to push against the end of cam i , which is attached to the side of disk x , said disk being held against gear 1 by means of the spring f , which produces sufficient friction between the gear and disk to cause said disk to revolve with said gear when the end of cam i is not in contact with arm a' . Said spring f does not produce so much friction between the gear and disk as to prevent said disk from being turned by the arm a' in the opposite direction from the movement of gear 1.

The arm a''' is attached to gear 2, and has its lower end held against cam i' by means of the weight W on the arm I, acting through gears 4 3 2. The weight W also acts to move to the right, through the gears 4 5 6, the gear-rack 7, which is supported and guided by the bracket h . The bar f'' is hinged to gear-rack 80 7, and has projecting from it the foot g . The bar f'' and the arm g' , which is attached to the same shaft that the lever b' is attached to, are in the same vertical plane, so that in whatever position, right or left, rack 7 may be 85 moved said bar remains over said arm.

m m' m'' represent three numbered plates, which slide perpendicularly in the guide-pieces C, and are held in position by means of three pivoted spring-latches, n , which latch 90 onto the catches o . Projecting from these latches are the arms n' , which are located in a horizontal plane just above the foot g . The escape-wheel 8, with its pendulum n'' , regulates the speed of gear 1.

Having described the mechanism of my improvement and set the apparatus ready for action, which has to be done after each alarm by placing the numbered plates at their extreme height of movement with their corresponding numbers horizontal with each other—rack 7 to the extreme left of its movement, gear 1, with its drum c' and ribbon of paper held by hooked lever b , disk x , with its cam i' supporting the

lower end of arm a'' , and its cam i , with its end at the left held within a short distance of the arm a' —its operation is as follows: For illustration, 5 a fire occurs in district 211. Now, when the alarm is put into operation and is receiving its first stroke upon the bell, it puts in motion the lever D , which actuates lever G and causes the recording-point b' to perforate the paper, and at the same time releases the hooked lever b from one of the pins e , which allows the weighted 10 ribbon of paper to set gear 1 in motion, which unwinds the paper from the roll d' , so as to present a fresh surface to the recording-point at the next stroke of the alarm. The first stroke 15 of the alarm not only released the hooked lever b and perforated the paper, but it also moved arm a' and the lever b' , which rests against it, which causes the arm g' to lift the bar f'' with its foot g , which lifts the arm n' of the latch n , and thus releases said latch from 20 the first lower catch, o , on numbered plate m , and allows said plate to drop down until it is caught on the second catch, o' , by the reaction of latch n , thus bringing to view (through an 25 aperture in a suitable covering over the plates $m m' m''$, not shown in the drawings) the number of the stroke on the bell, which is 1. Should a second stroke of the bell occur (as it will in this instance) within an interval of three seconds, 30 the above operation will be repeated and bring to view number 2 on plate m . Thus each stroke, with an interval of three seconds, up to the number of ten is shown from plate m . While arm a' is moving lever b' (as it does 35 at each stroke of the bell) it also pushes the disk x and its cams forward to a certain point, which at the first stroke of a figure shifts the position of the end of arm a'' from cam i' to cam i . The arms G and a' drop back after 40 each stroke of the bell, but the disk and cams do not instantly follow said arm a' back, but, being held in frictional contact with gear 1, are slowly returned toward their first position as gear 1 is rotated by weight e , its speed being 45 regulated by the escapement. During the space of three seconds between the strokes of a figure, so to speak, the cams cannot move back far enough to let arm a'' escape from cam i ; but when the disk moves back far enough 50 for the space of five seconds before being driven forward again by arm a' the end of arm a'' is permitted to escape through the space between the two cams i i' , and thus free itself from said cam i , which will allow said arm a'' , with its gear 2, to make a revolution which will bring 55 the end of the arm to its first position on cam i' and the foot g under the arm of the latch that holds up plate m' . Should the bell be struck again after the interval of five seconds, as it is in this instance, the apparatus is put 60 in motion and the stroke of the bell is shown from plate m' , which is 1, and which is recorded in a space by itself on the paper, as in the action of the first stroke of the bell. After the number of the stroke has been indicated 65 from plate m' and recorded, the above operation is repeated to cause plate m'' to indicate a stroke of the bell, which is also recorded, thus completing the first round of strokes for district 70 211, after which, whether said round is indicated, as in the present instance, by three figures or by one or two figures, there occurs an interval of twenty seconds, during which gear 1 has turned disk x far enough backward 75 to allow the end of arm a'' to pass off the end of cam i' , which allows gear 2 to be revolved by weight W and carry rack 7 to the extreme right, away from any subsequent action of foot g' . After the number of the district has been indicated and rack 7 moved to the extreme 80 right, the recording mechanism continues to act, recording the number of the district in separate spaces on the paper, until the alarm has been given a proper number of times. Thus any number of the strokes of the alarm 85 indicating the district where the fire occurs is indicated but once and recorded as many times as given by my improved combination of mechanism.

What I claim, and desire to secure by Letters Patent of the United States, is—

1. In a fire-alarm indicator and recorder, the lever G , having attached to it the perforating-point b' and the two arms a a' , which are in combination with levers b b' , arm g' , bar f'' , 95 foot g , arms n' , latches n , and plates m m' m'' , all arranged in the manner and for the purpose specified.

2. The lever G , arm a' , and friction-disk x , with its cams i i' , in combination with gear 1, arm a'' , and gear 2, all of which are arranged and operated substantially as and for the purpose set forth.
